(57) **CLAIM**

The ornamental design for a contact assembly for a battery, as shown and described.

DESCRIPTION

FIG. 1 is a front perspective view of a contact assembly for a battery showing the new design;

FIG. 2 is a rear perspective view of the contact assembly for a battery shown in FIG. 1;

FIG. 3 is a top plan view of the contact assembly for a battery shown in FIG. 1;

FIG. 4 is a right side view of the contact assembly for a battery shown in FIG. 1;

FIG. 5 is a bottom plan view of the contact assembly for a battery shown in FIG. 1;

FIG. 6 is a left side view of the contact assembly for a battery shown in FIG. 1;

FIG. 7 is a rear view of the contact assembly for a battery shown in FIG. 1; and,

FIG. 8 is a front view of the contact assembly for a battery shown in FIG. 1.
